(57) **CLAIM**

The ornamental design for an atomizer tube, as shown and described.

DESCRIPTION

FIG. 1 is a perspective view of the atomizer tube showing my new design, shown in an environment of use;

FIG. 2 is a perspective view of FIG. 1, illustrated with environmental atomizing base removed for clarity of disclosure;

FIG. 3 is a front elevational view of FIG. 2, the rear elevational view, left-side elevational view, and right-side elevational view all being identical thereof;

FIG. 4 is a top plan view of FIG. 2;

FIG. 5 is a bottom plan view of FIG. 2; and,

FIG. 6 is a cross-sectional view thereof, taken along line 6--6 of FIG. 4.

The broken lines showing an atomizing base in FIG. 1 depict environmental matter and form no part of the claimed design. The remaining broken lines depict portions of the atomizer tube that form no part of the claimed design.
